UNITED STATES PATENT OFFICE.

JACOB J. DILLENBECK, OF PULASKI, NEW YORK.

TRUSS.

1,277,704.

Specification of Letters Patent.

Patented Sept. 3, 1918.

Application filed April 24, 1917. Serial No. 164,240.

To all whom it may concern:

Be it known that I, JACOB J. DILLENBECK, a citizen of the United States, residing at Pulaski, in the county of Oswego and State 5 of New York, have invented a new and useful Truss, of which the following is a specification.

The device forming the subject matter of this application is a truss, and one object of 10 the invention is to provide a structure of this kind which may be adjusted readily to the circumferential contour of the body of the wearer.

Another object of the invention is to provide 15 novel means whereby the parts may be adjusted to conform to the ruptures, and to conform to the back of the wearer.

It is within the province of the disclosure 20 to improve generally and to enhance the utility of devices of that type to which the present invention appertains.

With the above and other objects in view 25 which will appear as the description proceeds, the invention resides in the combination and arrangement of parts and in the details of construction hereinafter described and claimed; it being understood that changes in the precise embodiment of the invention herein disclosed can be made within 30 the scope of what is claimed, without departing from the spirit of the invention.

In the accompanying drawings;

Figure 1 is a perspective view disclosing a truss constructed in accordance with the 35 present invention;

Fig. 2 is a top plan of the truss;

Fig. 3 is a longitudinal section taken 40 through the clamp blocks and attendant elements, parts appearing in elevation; and Fig. 4 is a section taken on the line 4-4 of Fig. 2.

In carrying out the present invention there is provided a pair of springs 1 of bowed form and so constructed as to resist an outward expanding pressure. Since each spring 45 1 and attendant parts is a duplicate of the other spring and corresponding parts, the description will proceed in the singular number. Each spring 1 carries at its rear end a slide 2 mounted on the rear end of the spring for adjustment longitudinally of the spring. At its inner end, the slide 2 has 50 projecting fingers 3 which, engaging the upper and lower edges of the spring 1, permit a right line reciprocation of the slide 2 but prevent the slide from tilting on a stud 4,

which is carried by the end of the spring 1, and passes through an elongated slot 5 in the slide. A nut 6 is threaded onto the end of the stud 4 and bears against the slide 2, 60 the construction, obviously, being such that the slide 2 may be moved endwise and be held in adjusted positions. The slide 2 terminates in a reduced stem 7 carrying a ball 8 mounted to rock for adjustment in recesses 9 formed in the adjacent faces of an inner clamping block 10 and an outer clamping block 11; these blocks having enlarged notches 22 in their ends, the notches communicating with the recesses 9 and permitting the blocks 10 and parts carried thereby, as hereinafter described, to have practically a universal movement on the ball 8. The outer clamping block 11 is provided with an opening or duct 12, communicating with the recess 9 of the said block, and constituting means whereby the ball 8 may be lubricated. A screw 14 passes through the blocks 10 and 11 and enters a plate 15 constituting a part of a pad 16 held to the plate 80 by means of screws 17 or otherwise. From the description as thus far proceeded with, it will be obvious that the pad 16 may be shifted longitudinally of the spring 1, when the nut 6 is loosened, the slide 2 reciprocating on the spring. During this adjustment, the fingers 3 coact slidably with the upper and lower edges of the spring 1 and prevent the slide 2 and the pad 16 from swinging with the stud 4 as a center. By means of the screw 14, the blocks 10 and 11 are clamped down firmly on the ball 8, and thus the pad 16 may be held in adjusted positions. By loosening the screw 14, the pad may be adjusted on the ball 8. It is to be observed 95 that, as shown best in Fig. 2, the spring 1 terminates in spaced relation to the periphery of the plate 15, and consequently the plate and the pad may have a considerable degree of adjusting movement on the ball 8. 100

The plates 15, which carry the back pads 16, are provided with approaching extensions 18 supplied with slots 19 through which is passed a longitudinally elastic back strap 20, the ends of which are connected by a 105 buckle 21.

Mounted to reciprocate on the forward end of the spring 1, longitudinally of the spring is a slide 23 having rear fingers 24 engaging the upper and lower edges of the 110 spring 1, for the purpose specified hereinbefore in connection with the fingers 3. The

slide 23 has an elongated slot 26 through which passes a stud 27 carried by the forward end of the spring 1. A nut 28 is threaded onto the stud 27 and engages the forward face of the slide 23, to hold the same in adjusted positions longitudinally of the forward end of the spring 1. The numeral 29 designates a connector preferably in the form of a hook, having fingers 25 which extend across the upper and lower edges of the slide 23. The numeral 30 denotes an arm having a head 31 abutting against the rear face of the slide 23. The head 31 has a stud 32 passing through the forward end of the slide 23 and through the shank of the connector or hook 29. A nut 33 is threaded onto the stud 32 and engages the forward face of the shank of the hook. The arm 30 is provided with a ball like the element 8, the same being engaged between the blocks 34 of the kind hereinbefore described, the blocks 34 being held by a screw 35 to a plate 36 carrying a pad 37, it being possible by tightening up the screw 35 to prevent relative movement between the plate 36 and the pad 37 on the one hand, and the arm 30 on the other hand. The slide 23 may be moved endwise of the forward end of the spring 1, and, by loosening the nut 33, the arm 30 may be swung vertically with the stud 32 as the center of swinging movement. The fingers 25 on the hook 29 are short enough so that they do not interfere with the vertical swinging movement of the arm 30. These fingers, however, prevent the hook 29 from swinging vertically when the nut 33 has been loosened sufficiently so that the arm 30 can be swung vertically as aforesaid.

Plates 38 are provided, the same having 40 slots 39 receiving the hooks 29 detachably. The plates 38 are provided at their inner ends with slots 40 through which is looped a longitudinally elastic strap 41, the ends of

which are connected by a buckle 42 or otherwise. The specific construction involving 45 the strap 41 and the plates 38 may be changed without jeopardizing the utility of the invention, and if desired, if but a single rupture is to be retained, but one spring 1 with the pads 16 and 37 need be used, any 50 suitable means being provided for connecting the hook 29 with the extension 18.

The device is so constructed that the positions of the parts 16 and 37 may be adjusted and, further, the circumferential contour of 55 the device may be altered by manipulating the straps 20 and 41. Since the straps 20 and 41 are longitudinally elastic, the springs 1 are drawn toward each other, yieldingly, and the pads 16 and 37 (and particularly the 60 pad 37) are held in proper place.

Having thus described the invention, what is claimed is:—

In a truss, a body encircling member having free ends; a slide adjustable on one end of the body encircling member, longitudinally thereof; means for holding the slide in adjusted positions on said end of the body encircling member; a connector provided at one end with flanges which extend across the 65 upper and lower edges of the slide; an arm provided at one end with a stud passing through the slide and through the connector; a clamping device on the stud and co-operating with the connector; a pad carried by the 70 other end of the arm; and a flexible member 75 detachably assembled with the other end of the connector and with the other end of the body encircling member.

In testimony that I claim the foregoing as 80 my own, I have hereto affixed my signature in the presence of two witnesses.

JACOB J. DILLENBECK.
